UNITED STATES PATENT OFFICE

1,978,593

CRACKING HYDROCARBON OILS

Edwin F. Nelson, Chicago, Ill., assignor to Universal Oil Products Company, Chicago, Ill., a corporation of South Dakota

Application November 26, 1930, Serial No. 498,237

4 Claims. (Cl. 196—51)

This invention relates to the cracking of hydrocarbon oils and more particularly refers to the conversion of relatively heavy oils into lighter and more valuable products.

5 The primary concepts of the invention comprise introducing oil into a heating element wherein it may be raised to any desired conversion temperature, preferably under a substantial superatmospheric pressure, introducing the 10 heated products into an enlarged reaction chamber, also preferably maintained under a substantial superatmospheric pressure, passing the products of reaction to a vaporizing chamber, preferably maintained under a substantially reduced pressure, withdrawing unvaporized residual oil from the vaporizing chamber and returning portions thereof with or without cooling to the reaction chamber, for introduction, preferably at its point of outlet, subjecting vapors from said vaporizing chamber to fractionation, returning heavy insufficiently converted portions of the vapors to a heating element for reconversion, subjecting the relatively light fractionated vapors to condensation and cooling, and collecting the 20 resultant distillate and incondensable gas.

Further objects and features of the invention will become apparent upon reference to the attached diagrammatic drawing illustrating one form of apparatus in which the invention may be practiced and the following description, in which,—

Fig. 1 is a side-elevational view; and

Fig. 2 is a cross-sectional view of a form of control means for the outlet of a chamber which may be employed in my invention.

Referring to the drawing, raw oil charging stock may be supplied through a line 1 controlled by valve 2 to pump 3 and line 4, and may pass through a line 5 controlled by valve 6 into a fractionator 7 where it may be preheated by contact with the relatively hot vapors therein, assisting in their fractionation, and, together with the relatively heavy condensed components, may pass through a line 8 controlled by a valve 9 to a pump 10. Any desired portion or all of the raw charging stock may be diverted from fractionator 7 by passing directly through line 4 controlled by valve 11 into line 8 and thence to pump 10 for admixture with reflux condensate issuing from fractionator 7. The combined raw oil and reflux condensate supplied to pump 10 may then be fed through a line 12 controlled by valve 13 to a heating element 14.

Heating element 14 may be disposed in a suitable furnace 15 and the oil passing therethrough

may be heated to the desired conversion temperature, preferably under a substantial superatmospheric pressure, and may then pass through a line 16 controlled by valve 17 into a reaction chamber 18. Chamber 18 is preferably maintained under a substantial superatmospheric pressure, which may be the same or lower than that employed in heating element 14. The liquid and vaporous products issuing from chamber 18 may be withdrawn through a line 19 controlled by valve 20 and passed to a vaporizing chamber 21, preferably maintained under a substantially reduced pressure from that maintained in chamber 18. Vapors may be withdrawn from chamber 21 through a line 22 controlled by valve 23 and passed to fractionator 7 where they may be subjected to fractionation and their relatively heavy, insufficiently converted portions condensed and returned to heating element 14, as already stated. The relatively light fractionated vapors containing the desired components may be withdrawn through a line 24 controlled by valve 25 from said fractionator 7 and subjected to condensation in a condenser 26, the resultant products from which may pass through a line 27 controlled by valve 28 and collected in a receiver 29. Condensed distillate may be withdrawn from receiver 29 through a line 30 controlled by valve 31, and incondensable gas may be released therefrom through a line 32 controlled by valve 33. A portion of the distillate from receiver 29 may be withdrawn through a line 34 controlled by valve 35 and recirculated by means of a pump 36 through a line 37 controlled by valve 38 to fractionator 7 to assist in the fractionation of vapors therein.

Residual unvaporized products in chamber 21 may be withdrawn through a line 39 and may pass through control valve 40 to a cooler 41 and thence through a line 42 controlled by a valve 43 to storage or further treatment, as desired. Any desired amount of the cooled residual products may pass through a control valve 44 in a line 45 from said cooler 41 to a pump 46 for recirculation through a line 47 controlled by valve 48 to chamber 18. Said returned residual products are preferably discharged into chamber 18 at or near its point of outlet. If desired, instead of passing the residual products from chamber 21 through cooler 41, any amount thereof may be passed through a line 49 controlled by valve 50 directly to said line 49 and pump 46 for introduction into said chamber 18 through said line 47. Any other desired cooling medium, as for example, a portion of the raw oil charging stock from the system,

an intermediate product from said system, such as reflux condensate, or an extraneous oil, such as pressure distillate bottoms, gas oil, raw oil or residual oil, may be introduced into chamber 18 through a line 51 controlled by valve 52 communicating with line 46, pump 46 and line 47.

From the foregoing operation, it will be apparent that I am enabled to effect a control over the reaction proceeding within chamber 18, procure a decrease in carbon or coke formation therein, produce an improved residual product, prolong the operation and prevent carbon, coke, pitch or other similar deposition in the transfer line 19 between chambers 18 and 21, which would otherwise result in a stoppage or plugging thereof.

In order to control the withdrawal of residual products from chamber 18, as well as aid in further maintaining an open passageway between chamber 18 and 21, I may interpose at the point of outlet of chamber 18 and communicating with the entrance to transfer line 19, a suitable form of control means, having a valve disc 55 adapted to seat against the entrance of said line 19 which may be raised or lowered by a hand wheel 56 threaded to a valve stem 57 on which the valve disc 55 may be mounted. Valve stem 57 may be suitably supported by a yoke 58, apertured to receive a suitable packing gland 59.

The cooling medium from line 47 may enter chamber 18 in the form of a stream under pressure at a point preferably concentric with and approximating the entrance of line 19 against which valve disc 55 may be seated when in closed position, thereby preventing carbon deposition and maintaining a free and open communication for said line when the valve disc 55 is unseated.

The pressures employed within the system may range from sub-atmospheric to superatmospheric to as high as 2000 pounds per square inch, or more. Preferably, superatmospheric pressure of the order of several hundred pounds per square inch may be employed in the heating element and in the reaction chamber. This pressure may be substantially equalized, or a lower pressure may be employed in the reaction chamber than in the heating element. The vaporizing chamber is preferably maintained under substantially reduced pressure, relative to that employed in the reaction chamber, and the fractionating, condensing and collecting portions of the system may be maintained under substantially the same or lower pressure than that employed in the vaporizing chamber. Conversion temperatures employed may range from 750 to 1200° F., more or less.

I have found that with a temperature at the outlet of the heating coil approximating 950° F., and a pressure of substantially 300 pounds per square inch on said heating coil and in the reaction chamber, yields of 65% gasoline, having

an anti-knock value of 60% benzol equivalent may be obtained. Through the medium of the introduction of the cooling medium to the reaction chamber, as hereinbefore described, an operating period several times the duration of that effected when no cooling medium was employed, also resulted.

I claim as my invention:—

1. A chamber adapted for use in an oil cracking process, comprising in combination, an inlet and outlet therefor, a regulating valve for said outlet, and means for introducing a cooling medium to said chamber in a stream substantially concentric with the valve control on said outlet.

2. A hydrocarbon oil cracking process which comprises passing the oil in a restricted stream through a heating zone and heating the same therein to cracking temperature under pressure, discharging the heated oil into an enlarged reaction zone maintained under cracking conditions of temperature and pressure and effecting further reaction of the oil therein, removing liquid and vaporous reaction products as a mixture through a discharge line at the bottom of the reaction zone and introducing the mixture into a separating zone maintained under lower pressure than the reaction zone, separating the mixture into vapors and unvaporized oil in the separating zone, removing unvaporized oil from the separating zone and introducing the same to the reaction zone adjacent the point of withdrawal of said mixture therefrom and injecting it downwardly into said discharge line.

3. A hydrocarbon oil cracking process which comprises passing the oil in a restricted stream through a heating zone and heating the same therein to cracking temperature under pressure, discharging the heated oil into an enlarged reaction zone maintained under cracking conditions of temperature and pressure and effecting further reaction of the oil therein, removing liquid and vaporous reaction products as a mixture through a discharge line at the bottom of the reaction zone and introducing the mixture into a separating zone maintained under lower pressure than the reaction zone, separating the mixture into vapors and unvaporized oil in the separating zone, removing unvaporized oil from the separating zone and cooling the same, and introducing the cooled unvaporized oil to said reaction zone adjacent the point and in the direction of withdrawal of said mixture therefrom and injecting it downwardly into said discharge line.

4. A chamber adapted for use in an oil cracking process, comprising in combination, an inlet and outlet therefor, a regulating valve seated against said outlet, and means for introducing a cooling medium to said chamber in a stream substantially concentric with said valve.

EDWIN F. NELSON.
